George H. Mandel

UNITED STATES PATENT OFFICE.

ANDREW FUERTINGER, OF NEW YORK, N. Y., ASSIGNOR, BY MESNE ASSIGNMENTS, TO VOICES INCORPORATED, OF WILMINGTON, DELAWARE, A CORPORATION OF DELAWARE.

VOICE DEVICE.

Application filed March 20, 1925. Serial No. 17,104.

This invention relates to a voice device of the type customarily used within the bodies of dolls, and in similar locations and for producing word sounds such as "ma-ma," the production of sounds being caused by movement of the doll from one position, say an upright position, to another, say a reclining position.

The present invention is in the nature of an improvement over what is shown and described in the pending application of L. Gessford Handy, Serial #757,845, and a particular object is to improve the manner of mounting and controlling the movable valve member employed and for thereby simplifying and rendering more efficient the construction and operation of the mechanism.

Other objects and aims of the invention, more or less specific than those referred to above, will be in part obvious and in part pointed out in the course of the following description of the elements, combinations, arrangements of parts and applications of principles constituting the invention, and the scope of protection contemplated will be indicated in the appended claims.

In the accompanying drawings which are to be taken as a part of this specification, and in which I have shown merely a preferred form of embodiment of the invention:

Fig. 1 is a vertical sectional view through a voice device constructed in accordance with this invention.

Fig. 2 is a horizontal sectional view taken substantially upon the plane of line II-II, a part of the structure being broken away to disclose further detail, and

Fig. 3 is a fragmentary detail sectional view corresponding with the central portion of Fig. 1 and illustrating a modification of the form and mounting of the valve controlling element.

Referring to the drawings for describing in detail the structure therein shown the reference character L indicates a suitable casing. This may be of any appropriate construction and is adapted to contain the movable parts of the device. In the instance illustrated it consists of a pasteboard cylinder 1, which forms the sides walls of the casing, and top and bottom walls 2-2, of sheet metal.

Within this casing is arranged a weight G 55 adapted to slide longitudinally of the casing. This weight constitutes the movable head of a bellows, the opposite member or head of the bellows being the bottom wall 2 of the casing, and the bellows being completed by a soft flexible cylindrical member 3 which connects said heads.

The head G has a central bearing opening 4 by which it is slidably mounted upon a central rod 5, the rod 5 being in turn fixed, preferably by its opposite ends, to the casing L, as by being received in pits 6 formed in the walls 2-2 of the casing.

The head G is of sufficient weight so that it operates by gravity to distend and collapse the bellows member 3 whenever the casing is moved from an upright to an inverted position and vice versa, and it thus automatically produces sounding of a reed or like suitably sound producing element 7 76 carried preferably by the head G.

Within the head G is formed an appropriate sound box 8 with which the reed 7 communicates through a suitable opening 9.

An opening 10 is provided through the top wall member 11 of the sound box through which the sound waves from the reed and sound box must pass on their way to the outer atmosphere.

The top wall as 2 of the casing is perforated in the usual manner in order that the sound waves may pass freely out of the casing.

The wall member 11 of the sound box is 90 preferably formed of sheet metal. It is of inverted saucer shape and its lower annular edge portion has telescopic engagement with the annular edge portion of the head and serves not only to hold these two 95 parts in assembly but also to clamp the upper annular edge portion of the bellows member 3 in position upon the movable head.

The sound emitting opening 10 is concentric with the opening 4 and the material 100 of the wall 11 surrounding said opening is preferably bent inwardly and downwardly so as to prevent horn-like tapering walls 12 extending outwardly from said opening 10 which are effective in giving a gradually 105 increasing volume to the emitted sounds.

To control the passage of sound waves outwardly through the opening 10, and to

thereby determine the operation of the reed 7 and the inflections of the passing sound waves, the present invention utilizes the single separately formed valve member H 5 mounted to move to and fro through the opening 10 during the operation of the bellows. This valve member has a central bearing opening 13 by which it is slidably mounted upon the rod 5.

10 Aligned with the opening 10 the main portion of the head G is provided with the dash-pot 14 directly below said opening 10 and of a size to receive the valve H when said valve slides down the rod 5, the relation of the valve to the dash-pot being such that the falling movement of the valve will be retarded to a suitable extent to properly time the valve movement in proportion to the movement of the head, in the same manner more fully set forth and described in the 20 pending application above referred to.

Carried by the main portion of the head G is a separately formed stop rod 15 which is arranged parallel with the rod 5 and which is adapted to slide freely through a bearing opening 16 formed in the head G beneath the valve H. It is provided with upper and lower shoulders 17 and 18 to prevent its disengagement from the head at all 30 times.

As the head G, with the valve H, slides downwardly along the rod 5, the lower end of the rod 15 comes into engagement with the upper surface of the bottom wall 2 of the casing and the upper end of the rod 15 serves to support the valve H positively against further downward movement.

In the operation of the device, assuming the casing to have been just returned to an 40 upright position after being inverted, the stop rod 15 will move downward through the opening 16 to the position indicated, the head G will begin to descend and the displaced air from beneath it will cause sounding 45 of the reed. These initial waves, passing into the sound box 8, will issue therefrom in a much subdued manner through the opening 10, it being noted that at this time the valve H is standing within said opening 50 and that the valve is sufficiently smaller than said opening so as to leave a crevice as 19 between itself and the walls of the opening of just the right size to produce the desired result, that is the momentary purring or 55 nasal sound "mm" preceding, or forming the initial part of, the first syllable of the word "ma-ma".

The valve H has also begun to slide down the rod 5. Except for the presence of the 60 dash-pot 14 this valve would fall almost instantly out of the opening 10. The fall of the head G is relatively slow because of the requirement for displacing air from within the bellows, but the valve H has not this resistance to control with. It has merely the

dash-pot 14 to overcome and its relation to this is just such as to properly time the fall of the valve relative to the fall of the head G.

As the parts continue to fall, and the valve H finally drops out of the opening 10 the 70 sound waves will pass freely from the sound box and produce the main portion of the first syllable of the word "ma-ma".

During at least a part of this period the 75 weight of the valve will be in varying degrees added to the weight of the head G and will increase the gravity pull of said head accordingly. A slight but desirable inflection of the sound waves will at this time be thus produced.

As the parts continue to further descend the rod 15 will be brought to rest by engagement against the bottom wall of the casing and the valve H will be likewise brought to rest by being supported upon the 85 upper end of the rod 15.

The first syllable of the word "ma-ma" will be terminated by thus closing the opening 10, and a second purring on nasal sound "mm" will result from the again restricted 90 passage through which the sound waves must pass from the sound box.

As the head G fell away from the stationary valve H the dash-pot action between the valve and the dash-pot 14 caused a reduction 95 in the gravity pull of the head and the force, or draught, of air through the reed was momentarily reduced just prior to the termination of the first syllable "ma" so that said syllable ended smoothly and merged gradually into the purring or "mm" sound with a desirable inflection of the sound waves.

The second, or intermediate, purring "mm" sound will continue until the valve has again passed through the opening 10, or 105 rather until the head G has fallen so that the opening has moved entirely free of the valve. As the dash-pot 14 fell free of the valve the head suddenly resumed its normal speed of descent and there was present for 110 the moment an excess of air pressure through the reed. This occurred at a moment when the valve stood directly within the opening 10 and caused the purring "mm" sound then issuing from the device to be momentarily 115 accentuated and thereby given a desirable and natural inflection closely approximating the exasperated cry of an infant.

The second or final syllable of the word "ma-ma" will begin to sound as the opening 120 10 passes below the lower edge of the valve and will continue so long as air continues to move through the reed, that is until the head G comes to rest in its lowermost position against the bottom wall 2 of the casing.

By shaping the top wall member 11 of the sound box with its portion forming the opening 10 bent inwardly there is provided not only the outwardly flaring horn-like portion 12 for gradually increasing the volume 130

of sound produced, but other results are accomplished among which may be mentioned the fact that the lower end portion of the inturned part may be suitably extended to form a parallel walled tubular portion 20 at the lower end of the horn-like portion 12. This tubular portion may be given suitable vertical length to provide the desired amount of resistance to the passage

10 of air during the "mm" periods without requiring a too close fit of the valve H therein. Also it will provide a surface portion as 21 which may engage against the inner surface of the top cover member 2 to limit 15 movement of the head G toward said cover member and to thus accurately define the position of the head G preliminary to each operation of the device, it being noted that the extreme position of the valve H is limited by engagement with the same cover member, or against a cushion member 22 fixed to said cover member.

The cushion member 22 as illustrated is interposed between the upper end surface of 25 the rod 5 and the adjacent inner surface of the cover member 2 and extending into the pocket 6. In this way it serves not only to cushion movements of the valve H against the cover member but it also constitutes a 30 soft resilient filler between the cover member and the end of the rod and to thereby insure that said rod will be firmly held in position without necessity for imposing any undue strains upon either of the cover members.

35 It has been the practice heretofore to make the central standard or rod as 5 considerably longer than the normal distance between the inner surface of the opposite cover members and then when assembling 40 the device, to apply said cover members by a force sufficient to cause the cover members to bow outwardly and thus accommodate the rod. By firmly attaching the cover members onto the opposite ends of the cylinder 1 the bowed condition of the covers has been maintained and a suitable resilient grip thus applied upon the rod so as to hold it firmly 45 against rattling or dislodgement from its appointed position. It has not infrequently occurred however that the strain upon the 50 connections between the cover members and the pasteboard cylinder has caused said connections to become loosened. In manufacturing these devices in large numbers it is 55 practically impossible to carefully inspect each for defects in the joints between the cylinders and the cover members and although great care is exercised to make these joints sufficiently strong to withstand the 60 strains mentioned yet defective joints frequently occur and because of the strains to which they are subjected quickly develop a positive failure when the device is placed in use or subjected to the shocks and jars ordinarily experienced.

The arrangement of the cushion 22 in the manner described provides the necessary resiliency of grip between the cover members and the rod and holds the rod against rattling or movement with little or no bowing of the cover members, and thus avoids the excessive strains upon the connections between the cover members and the cylinders.

In the modification Fig. 3 the structure 75 is the same as herein above described except that in this instance the rod 15 of Fig. 1 takes the form of a small tube 23 slidably mounted directly upon the rod 5 and within the bearing opening 4 of the head G. Its opposite ends are provided with shoulders 17 and 18 as before and its operation for controlling the movements of the valve H are identical as already described with respect to the rod 15.

80 As many changes could be made in this construction without departing from the scope of the invention as defined in the following claims, it is intended that all matter contained in the above description or shown 85 in the accompanying drawings, shall be interpreted as illustrative only and not in a limiting sense.

Having thus described my invention, what I claim as new and desire to secure by Letters Patent is:—

1. In sound producing and controlling devices, a sounding device, a gravity movable member for causing a flow of air to operate said device, said member having a sound emission opening, and an independent valve element unattached to said member and movable by gravity with respect thereto to control the emission of sound through said opening, and means cooperatively engaging 100 one of said parts to effect a relative gravitational movement between said parts and produce an articulated emission of the sound.

2. A voice device comprising a bellows 110 having a head adapted to move by gravity for expelling air from the bellows, a sounding device arranged to be sounded by the outgoing air, said head having an opening through which the sound issues, a casing for 115 said parts, a rod fixed within and to the casing upon which the head is slidably supported, a valve member for said opening also slidable upon said rod, and a control member for said valve member also slid- 120 able upon said rod.

3. A voice device comprising a bellows having a head adapted to move by gravity for expelling air from the bellows, a sounding device arranged to be sounded by the 125 outgoing air, said head having an opening through which the sound issues, a casing for said parts, a rod fixed within and to the casing upon which the head is slidably supported, a valve member for said opening 130

also slidably upon said rod, and a control member for said valve member slidably mounted partly upon said rod and partly upon said head.

4. A voice device comprising a bellows having a head adapted to move by gravity for expelling air from the bellows, a sounding device arranged to be sounded by the outgoing air, said head having an opening through which the sound issues, a rod upon which the head is slidably supported, a valve member for said opening also slidable by gravity upon said rod, a separately formed control rod carried by and movable with said head, said control rod being also slidably upon said head in the path of movement of the valve member to engage therewith and being adapted by engagement with another portion of the bellows to slide relative to said head for thereby engaging said valve to control said valve.

5. A voice device comprising a bellows having a stationary head a movable head and a flexible tubular part connecting said heads, a guide rod connected with the stationary head and extending through a bearing opening in the movable head whereby the movable head is slidably supported to move in a direction toward and away from the stationary head, the movable head being adapted to slide by gravity along said guide rod, a sounding device arranged to be sounded by air displaced by movement of the movable head toward the stationary head, the movable head having an opening therein through which the sounds issue, a valve member for said opening also slidable by gravity upon said rod, a separately formed control rod for said valve member extending longitudinally parallel with said guide rod in the path of movement of the valve member and having engagement with the movable head to move therewith and into and out of engagement with the stationary head, and the engagement of said control rod with said movable head being of a character to permit the control rod upon engagement with the stationary head to itself become stationary while not interfering with the movement of the movable head whereby to control the operation of the valve member.

6. In sound producing and controlling devices, a sounding device, a gravity movable member for causing a flow of air to operate said device, said member having a sound emission opening, an independent valve element unattached to said member and mov-

able by gravity with respect thereto to control the emission of sound through said opening, a common means restricting the independent gravity movement of said member and valve element along parallel paths, and means adapted to cooperate with one of said parts to effect a relative gravitational movement between said parts and produce an articulated emission of the sound.

7. In sound producing and controlling devices, spaced relatively fixed parts, a sounding device, means arranged between said fixed parts for causing a flow of air to operate said device and said means including a gravity movable member having a sound emission opening, a guide for said member mounted between said fixed parts, a valve element controlling emission of sound through said opening also movable by gravity on said guide independently of said member, and means for causing a relative movement between said member and the valve element to effect an articulated emission of the sound.

8. In sound producing and controlling devices, spaced relatively fixed parts, a sounding device, means arranged between said fixed parts for causing a flow of air to operate said device and said means including a gravity movable member having a sound emission opening, a guide for said member mounted between said fixed parts, a valve element controlling emission of sound through said opening also movable by gravity on said guide independently of said member to effect an articulated emission of the sound, and means carried by said member controlling such independent gravity movement of the valve element.

9. In sound producing and controlling devices, a sounding device, means for causing a flow of air to operate said device including a gravity movable member, a sound receiving chamber carried by said member having a sound emission opening in its wall, a valve element independent of said member and movable by gravity through said opening and controlling the emission of sound therefrom, and means carried by said member to cooperate with the valve element and limit its independent gravity movement while permitting of the continued gravity movement of said member to thereby effect an articulated emission of the sound.

In testimony whereof I affix my signature.

ANDREW FUERTINGER.
